Higgs.

UNITED STATES PATENT OFFICE.

GEORGE WALLACE TIBBETTS, OF WINTHROP, MASSACHUSETTS.

BANKER'S BOOKLET.

1,331,598.

Specification of Letters Patent.

Patented Feb. 24, 1920.

Application filed June 22, 1916. Serial No. 105,264.

To all whom it may concern:

Be it known that I, GEORGE WALLACE TIBBETTS, a citizen of the United States, and a resident of Winthrop, in the county of 5 Suffolk and State of Massachusetts, have invented an Improvement in Bankers' Booklets, of which the following description, in connection with the accompanying drawings, is a specification, like characters on the 10 drawings representing like parts.

This invention relates to booklets for bankers' use and in particular to a booklet which may be utilized in administering one of the so-called "Christmas clubs" wherein 15 there are made periodical deposits of small amount to be returned in a lump sum at some given time as, for example, just before Christmas. The purpose of the invention is to provide such a booklet which will not 20 only make the accounting work of the bank simple and easy but which will stimulate and extend its business.

My invention will be best understood by reference to the following description taken 25 in connection with the accompanying drawings, wherein I have shown one form of booklet adapted for my purpose and wherein:

Figure 1 is a view of the book open to the 30 first leaf or page;

Fig. 2 is the book open to the second page; Fig. 3 shows the book open to one of the 35 pages of the body thereof; and

Fig. 4 shows the last page.

I will first briefly describe the physical 40 structure of the booklet shown in the accompanying drawings, disregarding for the moment the principles which underlie the choice of elements and their combination in coöperative relationship. Referring to Fig.

1, it will be seen that on some part of the 45 book, preferably a permanent part thereof as on the inside 3 of the cover, are printed the rules governing the club, that is, the contract entered into between the bank and the

depositor. The first page 5 may be made of 50 comparatively stiff card or similar material and is detachable, for example, by means of the scored division line 7. This blank is intended to be detached by the bank when the

account is opened and the printed matter 55 thereon includes a memorandum of agreement 9 referring to the rules or contract, which are printed on the inside cover at 3 and thus brought to the depositor's notice.

Blanks 11 are provided for the depositor's 60 signature and there is also a blank form 13

which may, if desired, extend on the reverse of the leaf, as shown in Fig. 2, and provides a place whereon the bank can record the various payments or deposits. The records 60 of payments and deposits on this blank are similar to the postings in a ledger and the card with the postings thereon is really a ledger account for the depositor which may be filed away in a card drawer in any suitable manner. The leaf, furthermore, is a 65 signature card identifying the signature of the depositor and a memorandum of the contract which he has entered into with the bank. As shown at 15, the card bears a 70 designating mark such as a serial number which is repeated on all the leaves of the book so that although detached they may be readily classified or brought together again.

Referring now to Fig. 2, the second leaf 17 75 may constitute a receipt record on which the bank notes the various deposits as they are made. This record is permanently bound to the book and is retained therewith by the customer. The printing on this leaf may be 80 a suitable form of tabulation as indicated. Referring now to Fig. 3 the remainder of the book includes a number of detachable leaves 19, each of which is a deposit slip or 85 voucher for one of the periodical deposits. It is intended that these leaves should be detached from the book at the bank and handed in when the deposit is made. As shown at 15, these leaves bear the designat-

ing number of the account and bear the relation to the records on the card 5 that journal 90 entries do to ledger entries. The leaves 19 do not require to be written on or treated in any way and consequently there is no delay in handling the deposit at the teller's 95 window. As an example of the letterpress which may be printed on this leaf there may be beside the account number 15 a number indicating the particular periodical deposit and a statement of the amount. An important 100 feature of my invention consists in the fact that on each of the deposit slips or vouchers is printed a clause of the contract between the depositor and the bank which is an order to the bank to apply some of the 105 deposited money to a restricted account. The importance of this feature will more fully appear hereinafter. As an example of the letterpress that may be used, the following may be given:

"It is agreed by the depositor that \$5.00 (or the total deposit if less than \$5.00) shall

be transferred to the Savings Department of the Bank on December 15th, that being the end of the club term, same not to be withdrawn for ninety days thereafter. The 5 balance of all deposits and interest, if any be due, may be withdrawn December 15th."

It will be understood that this is one of the rules printed on the cover 3.

I prefer, furthermore, to add to the book 10 a detachable leaf 21 which is a blank order that may be filled out at any time directing that the entire sum due under the contract or any part thereof be transferred to a restricted account such as one in the savings 15 department of the bank.

The utility of my invention is twofold. First, it provides a convenient and inexpensive way for administering the accounts of a "Christmas club"; secondly, it will extend 20 the clientele of the bank and will have the tendency to bring customers into its savings department. The so-called "Christmas clubs" wherein periodical deposits are made to provide against the heavy expenses 25 of Christmas time have been instituted by banking houses with two primary purposes. The first is to bring persons to the bank in the hope that they may become profitable customers or clients thereof. The second 30 purpose has been to show by force of example the benefit of regular savings. The importance of the Christmas club accounts in themselves is not great as the amounts are small and there is a good deal of clerical 35 work involved in their administration. By the use of my invention not only is the primary advantage to the bank of the small accounts increased but the underlying purposes of the scheme are much advanced.

40 It will have been apparent from the description of the form of the book as used that the method of keeping the accounts is considerably simplified. The card 5 which is filled out by the customer before or when 45 he comes to the bank serves three purposes. It is a ledger account, it is a signature card and it is a memorandum of the contract between the customer and the bank signed by the customer. The deposit vouchers 19 are taken 50 in by the teller across the counter and by means of the numbers 15 the card or ledger account can be posted from such slips. The receipts for the deposit are entered by the teller in the form provided on the leaf 17 as 55 he detaches the slip.

A further advantage of the use of the book with the leaf 5 as described is that it lends itself for distribution to prospective customers. In other words, instead of inducing 60 persons by advertising to come to the bank and go through a certain amount of trouble in opening an account, it is possible to distribute the books themselves and thus suggest to persons the advantages of the scheme. 65 Then if at any moment the person receiving

the book feels that he would like to enter the club, he simply signs the deposit card 5 and either hands it over the counter of the bank without waiting, or mails it to the bank. By such means many customers are 70 retained who would change their minds or omit to go to the bank to start the account when it involved a certain amount of initial inconvenience. It will be noted that the signature to the card is a memorandum of a 75 contract entered into between the customer and the bank the terms of which are brought to the customer's attention in the same book from which he detaches the slip and preferably by having them printed directly opposite them, as shown in Fig. 1. An important feature consists in the manner in which the club may be administered by the use of my invention. As stated, one of the purposes of these Christmas clubs is to 80 induce persons to become depositors in one of the regular branches of the banking house after they have had an object lesson in the advantage of regular saving. For this purpose I prefer to embody as a term of the 85 contract an agreement that some part of the accumulated sum on deposit shall not be withdrawn at the conclusion of the club term just before Christmas, but shall be transferred to the regular savings branch of the 90 bank to lie there for a certain specified period. By this means an initial start is made on a regular savings account automatically as it were, and it is probable that the depositor will continue the same and add 95 thereto as he has done in a similar way in the Christmas club. For example, if he omits to join the club for another year for any reason and afterward repents of his 100 decision, he will already have an account to 105 which he can add deposits. Furthermore, the limitation of the account is such that it cannot be withdrawn at Christmas time when extra spending money is so desirable, but will be carried over into a later period 110 when the credit, in the popular phrase, will be just like finding money. Therefore, the customer will probably let the account stand and the bank has the beginnings at least of a 115 profitable client. Preferably, as explained, 120 the clause of the contract bearing on this point is printed upon each of the deposit vouchers or slips. This idea is periodically presented to the mind of the holder of the book as a suggestion and by its repetition 125 his mind grows accustomed to the idea of having a savings account and the suggestion is reinforced by the considerations of the advantage which he knows will arise therefrom. The result of this systematic suggestion is much more certain than a single or infrequent argument which might in itself be more striking. Therefore, the tendency is to make more probable the indefinite utilization 130 of the savings account started by a

part of the Christmas club fund. To take advantage of any favorable condition in the mind of the holder of the booklet I prefer to bind as a part of the booklet, preferably on paper of some contrasting color, the detachable transfer order 21, which will transfer the whole Christmas club fund or a part thereof to a regular savings account. Thus, if at any time the holder of the booklet is momentarily convinced of the advantage that would come to him through having a savings account, it is only necessary for him to remove the slip which is already appended and hand it or mail it to the bank. There is comparatively little opportunity for him to let the matter slip through neglect or by postponement to a more convenient time.

It is apparent from the above brief description of a few of the typical advantages arising from the use of such a booklet as I have described that not only is the administration of a Christmas club or similar scheme facilitated, but that through the same agency that is utilized for administering the scheme the business of the bank may be built up and extended along substantial and profitable lines. It is, of course, obvious that the particular arrangement of parts

and the letterpress utilized in the booklet here shown, are not of the essence of the invention but that they could be widely varied. What I do claim and desire to secure by Letters Patent is:

A booklet constituting a unitary application facilitating the inception and administration of banking transactions involving a plurality of deposits comprising, in combination, a detachable card having a memorandum of contract, a delineated blank space for signature and a blank form to receive a ledger account, a leaf having a similar blank form for the notation of receipts and a plurality of detachable leaves bearing printed matter and constituting deposit slips, the whole being bound together and all the elements having a common identifying number, the detachable card being adapted for retention by the bank at the inception of the series of transactions and the detachable leaves being adapted to be delivered to the bank on each deposit and the leaf having a blank form being adapted for retention by the depositor to receive notations of receipt of the several deposits.

In testimony whereof, I have signed my name to this specification.

GEORGE WALLACE TIBBETTS.
